UNITED STATES PATENT OFFICE.

FRED A. READ, OF LYNN, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-STITCHING MACHINE.

1,170,331.

Specification of Letters Patent.

Patented Feb. 1, 1916.

Application filed September 18, 1913. Serial No. 790,387.

To all whom it may concern:

Be it known that I, FRED A. READ, a citizen of the United States, residing at Lynn, in the county of Essex and State of Massachusetts, have invented certain new and useful Improvements in Buttonhole-Stitching Machines, of which the following is a specification, reference being had therein to the accompanying drawing.

10 This invention relates to buttonhole stitching machines, particularly of that type known to the trade as the "Reece" buttonhole machine, wherein a stitch frame carrying the stitch forming mechanism on the one hand and a work clamp or support on the other hand are relatively movable so as to enable the stitching to be carried along the sides of the buttonhole and around its end or ends. Such stitch forming mechanism 15 comprises usually an eye-pointed needle carrying the upper thread and below and opposed thereto the so-called "under sewing mechanism," which carries and operates an under thread in coöperation with the needle.

20 A sewing machine of this class is illustrated in prior patent of Dixon No. 695,039, dated March 11, 1902, which will supply many details and matters of description which may be for convenience omitted from the present 25 application.

The main object of the present invention is to afford an under sewing mechanism of efficient construction and operation and possessing the merit of simplicity and the advantages which pertain to simplified mechanism.

The further advantages hereof will either be set forth in the hereinafter following description or will be obvious to those skilled 40 in the art.

First will be referred to the preferred embodiment of the present invention as constituting an illustration of the same, and thereafter the novel features will be pointed out 45 in the claims.

In the accompanying drawings forming a part hereof Figure 1 is a right-hand side elevation of the front portion of a buttonhole stitching machine embodying the present invention. Fig. 2 is a rear elevation of the under sewing mechanism detached. Fig. 3 is a front elevation of the under sewing mechanism. Fig. 4 is a left elevation thereof. Fig. 5 is a front elevation of the 55 part shown in Fig. 1 in a different position

from Fig. 3. Fig. 6 is a top plan view of the under sewing mechanism. Figs. 7, 8, 9, 10, and 11 are details of the looper mechanism.

Similar reference numerals designate corresponding parts in the several figures.

Certain parts are shown and may all be as in said Dixon patent, requiring therefore no detailed or other description except to enumerate them. Such parts include the clamp frame 1, the casing 2 containing the needle bar 3, it carrying an eye-pointed needle 4 for manipulating the upper thread, said needle bar and its casing being in practice mounted in the stitch frame already referred to but not herein shown, the curb or cam casing 5 in practice secured to the movable stitch frame so as to travel with it under the clamp frame, said casing 5 having suitable adjustable headed bolts 6 which bear against smooth ways 7 at the under side of the clamp frame, the rod 8 deriving its motion from a cam in the stitch frame, the cutter 9 and its carrying lever 10, the under thread needle 11, the carrier 12 therefore, the fixed guide or race 13, the block 14, 80 said block having the circular upper end 15 adapting it to receive at suitable times a circular movement, the gear 16 fast on a sleeve 17 extending from block 14, the tension device 18 for the under thread, the 85 looper 19 and the throat plate 20; also the circular ring-like portion 21 of the casing 5, which receives within it the circular upper end 15 of the block 14, and depending from said ring 21 a loop 22 having formed 90 through it centrally at its lower end an opening of such size as to loosely receive hollow hub 23 of gear 16, the gear being applied to the sleeve 17 and fixed there by a suitable nut 24.

The sleeve 17 has extended through it the hollow rod or bar 25, said rod receiving through the opening in its lower end the second or underneath thread, such thread being passed upwardly through the rod 25 100 and into the under thread carrier 11. The thread may pass out of the hollow rod 25 through an aperture 26, passing about the tension device 18 before passing to the under thread needle 11. The rod 25 has fixed to 105 it below the gear 16 a ball or enlargement 27, it being as herein shown embraced between two loose cup-shaped disks 28 and 29, both loosely surrounding the rod 25 and contacting the ball 27, said disks being borne re- 110

spectively upon the two forks, 30, 31 of a lever 32 pivoted at 33 between two depending curved hangers, 34, 34, these hangers being connected in a suitable manner as by 5 screws 35, with the loop-shaped depending portion 22 above referred to. The lever 32 is connected with the rod 8 as shown so that the cam operated movement of the rod causes the oscillation of the lever 32 and 10 thereby reciprocates upwardly and downwardly the hollow rod or bar 25.

In continuing the description of the machine illustrated in the drawings hereof, I will refer to the new parts supplied by me 15 and to the new arrangements and combinations of parts, during which reference will necessarily be made to parts which *per se* are not new herein but are for the first time employed in the novel inter-relations and 20 arrangements which I seek to cover.

The oscillatory seat or so-called block 14, which may take any physical form, I shall term the "stock", as it is merely a carriage or frame for supporting the various working 25 parts of the under mechanism. It shifts bodily, for example circularly, with all of the working parts supported by it, and these parts themselves move as may be required for stitching more or less independently of 30 the stock's shifting.

Generally speaking the under sewing mechanism hereof comprises in combination the movable stock referred to, and the following elements supported by said stock, 35 namely, the movable under needle carrier 12, the movable thread looper 19, the movable actuator or up-and-down reciprocating rod 25, which is adapted to be exteriorly operated independently of the stock's shifting and connections hereinafter to be more 40 specifically described whereby said actuator actuates both said carrier and said looper.

Before describing the manner of actuation of the needle carrier and looper and the connections therefor, I shall refer to a convenient thread take-up or measuring contrivance shown herein, but which *per se* forms no part of the present invention. This comprises a three-armed lever, 36, 37, 38, 50 pivoted at 39, the long arm 36 having at its extremity an eye or aperture for the thread, the arm 37 having a spring 40 for turning the lever leftwise in Fig. 3, and the lever's oscillation being effected through a pin 41 on the up-and-down moving actuator rod 25. In order to adjust the movement of the lever an adjustable stop 42 is provided, a portion of which stands in the path of the arm 38 to limit to any desired degree the 55 upward movement thereof. It will be understood that the carrier 12 is provided with a thread guide, for example as shown at 43, with which the take-up arm 36 co-operates as in said Dixon patent.

60 The movement of the under needle carrier

12 is preferably a simple up-and-down swinging movement in the arc of a circle determined by the fixed guide or race 13, the needle first passing upwardly through the buttonhole to a position above the fabric 70 where it co-operates with the upper needle, the under needle then returning to a position beneath the fabric where it again co-operates with the upper needle by the aid of the looper 19. The operation of the 75 looper is not a simple swinging motion, but a compound motion consisting of the resultant of, first, an extended to-and-fro movement of the looper bodily between the needle paths and, second, a slight lateral 80 vibration serving to carry the barb of the looper around the path of the under needle. The purpose of such motion is that the looper may in moving toward the under needle path take a loop of upper thread at 85 each descent of the upper needle and present such loop to the under needle so that the latter may ascend through the loop causing an interlocking of the two threads.

Now will be described the following extremely simple trains of connections whereby the actuator 25 in its up-and-down movements effects actuation of the under needle carrier and also effects both motions of the looper. The train of parts for driving the 95 needle and its carrier 12 comprises stud 46 extending rearwardly from the actuator 25, intermediary or lever 47 having a slot connection with the stud and link 48 connecting the lever's upper end with a stud upon 100 the needle carrier 12. The lever 47 swings about an inclined pivot moving, therefore, in a plane parallel with the inclined plane of the needle carrier's movement, the stud-and-slot connection 46 being such as to allow 105 for the proper play in the movement of the parts.

It is proposed herein to give the looper 19 its proper described movements by means of a single device or cam. Heretofore it has 110 been usual to swivel the looper upon a carrying lever and swing the lever for producing the extended to-and-fro movement and oscillate the looper with respect to the lever for the slight lateral vibration. According to 115 the present improvement the looper is rigidly secured to its carrying lever 55 and the lever is accorded both of the necessary movements to effect the desired purpose. To this end the looper lever 55 is pivoted to the 120 stock by means of a universal pivot device 56, so constructed as to permit the lever to swing bodily in the plane of the paper in Fig. 3 and, at the same time, to vibrate about the pivot in a direction substantially 125 normal to the paper, these movements being subject to proper control, as will hereinafter appear. A downwardly extending portion or extension 57 of the looper lever serves the double purpose of a connection to the actu- 130

ator 25 and for control of the looper movement. A link 58, having a universal joint at each end, connects the actuator 25 and the looper lever extension 57 by means of studs thereupon as indicated. Thus the up-and-down actuator movements cause to-and-fro looper lever swinging movements.

Referring now to the universal pivot 56, its details are clearly indicated in Figs. 8 to 11. Extending forwardly from a fixed part of the stock 14 is a stud 61 surrounded by a brass sleeve 62 which forms the bearing for an outer sleeve 62^a. This construction is clearly shown in Fig. 8, which is a section taken on plane 8—8 of Fig. 3. The sleeve 62^a is, therefore, capable of rocking in a vertical plane about a forwardly and rearwardly extending horizontal axis. To this sleeve 62^a is movably connected the looper lever 55. A pivotal connection is shown in Fig. 9 which is a cross-section taken on the plane 9—9 of Fig. 8. Thus a pair of cone points 63, 63 are secured in the looper lever and engage recesses in the sleeve 62^a. This connection permits the looper lever to swing about an axis set substantially at right angles to the direction of the looper lever so that the lever may vibrate slightly out of its normal plane. It will thus be seen that the looper lever has a universal motion about the pivot device 55 which is in the nature of a gimbal.

So far as described, the looper lever would be freely movable about the cone point bearing and is controlled only in its to-and-fro movements about the central fixed stud bearing. It is proposed to employ a cam for effecting the vibration of the lever. A single surface cam 65 is preferred, this being shown secured to the stock 14 in such position that the lower end of the looper lever extension may ride over the curvatures of the cam. In order to keep the looper lever in contact with the cam a spring 66 is shown secured for convenience to the forward end of the stud 61 and at its free end engaging in a recess of and bearing rearwardly upon the forward side of the looper lever extension 57.

For the purpose of affording an adjustable and renewable connection between the looper lever and the cam the former is shown provided with a sliding block device 70 which may be secured upon the extension 57 in different positions by means of a set screw 71. A cam-contact screw 72 extends from the block 70 rearwardly through an elongated aperture in the extension 57 and into position to contact the forward side of the fixed cam 65, a lock nut 73 serving to confine the contact screw in adjusted position. Figs. 10 and 11 show these details, Fig. 10 being a cross-section on the plane 10—10 of Fig. 3, and Fig. 11 a cross-section on the plane 11—11 of Fig. 10.

Referring to Figs. 3 and 7 the cam 65 is

shown as having an outlying flange 67 at each end whereby the cam may be screw-connected to the stock 14. Fig. 7 best shows the contour of the cam and thereon the extreme positions of contact screw 72 are indicated at 68 and 69 respectively. The left-hand position 68 is that in which the looper barb is at its withdrawn or right-hand position. The operation is substantially that, during each stitch as the actuator 25 rises, it forces the looper lever extension to the right, thus shifting the contact screw across the cam from position 68 to position 69. Thus the bodily swinging of the looper toward the path of the under needle is accompanied by a slight lateral motion produced or controlled by the cam 65. The looper barb during this motion becomes gradually laterally displaced until at the high point of the cam the looper barb has passed by the path of the under needle whereupon the cam permits the looper to return slightly toward its normal plane, thus causing the barb to move directly behind the under needle, as desired.

It will thus be seen that there has been described a buttonhole stitching machine attaining the advantages recited and other advantages will be apparent to those skilled in the art. Since many matters of design, arrangement, combination, detail and other features may be afforded without departing from the principles hereof, it is not intended to limit the invention to such features excepting in so far as the same are specified in the appended claims.

What is claimed is:

1. In a buttonhole stitching machine, stitching mechanism including in combination, a work support, a reciprocable upper needle, a shiftable stock below the work support, and the following elements carried by the stock, an actuator operable independently of the stock's shifting but in harmony with the upper needle, a reciprocable under needle actuated from said actuator, a looper adapted to coöperate with said under needle by a compound movement, a downwardly extending rigid looper-carrying lever, a universal pivot between the stock and lever located a substantial distance beneath said looper, a connection whereby the actuator bodily swings the lever to and fro about said universal pivot, and an automatic device located substantially below said universal pivot and coöoperating with said lever for causing said lever to slightly vibrate about said universal pivot laterally to its to and fro movements.

2. In a buttonhole stitching machine, stitching mechanism including in combination, a work support, a reciprocable upper needle, a shiftable stock below the work support, and the following elements carried by the stock, an actuator operable in-

dependently of the stock's shifting but in harmony with the upper needle, a reciprocable under needle actuated from said actuator, a looper adapted to coöperate with said under needle by a compound movement, a downwardly extending rigid looper-carrying lever, a universal pivot between the stock and lever located a substantial distance beneath said looper, a connection 5 whereby the actuator bodily swings the lever to and fro about said universal pivot, and an automatic device for causing said lever to slightly vibrate about said universal pivot laterally to its to and fro movements. 10 15 20 25 30 35

10. In a buttonhole stitching machine, stitching mechanism including in combination, a work support, a reciprocable upper needle, a shiftable stock below the work support, and the following elements carried by the stock, an actuator operable independently of the stock's shifting but in harmony with the upper needle, a reciprocable under needle actuated from said actuator, a looper adapted to coöperate with said under needle by a compound movement, a downwardly extending rigid looper-carrying lever, a universal pivot between the stock and lever located a substantial distance beneath said looper, a connection whereby the actuator bodily swings the lever to and fro about said universal pivot, and an automatic device for causing said lever to slightly vibrate about said universal pivot laterally to its to and fro movements, said device comprising a cam and follower mounted one upon the lever and the other upon the stock substantially below said universal pivot and adapted to determine the looper's compound movement. 40 45 50 55 60

20. In a buttonhole stitching machine, stitching mechanism including in combination, a work support, a reciprocable upper needle, a shiftable stock below the work support, and the following elements carried by the stock, an actuator operable independently of the stock's shifting but in harmony with the upper needle, a reciprocable under needle actuated from said actuator, a looper adapted to coöperate with said under needle by a compound movement, a horizontal stud fixed on the stock a substantial distance beneath the looper, a sleeve movable about said stud, a recessed lever surrounding said sleeve, gimbal pivots between said lever and sleeve, said lever extending upwardly and

rigidly carrying the looper at its upper end, a connection whereby the actuator bodily swings the lever to and fro, and an automatic device for causing said lever to slightly vibrate laterally to its to and fro movements. 40

4. In a buttonhole stitching machine, stitching mechanism including in combination, a work support, a reciprocable upper needle, a shiftable stock below the work support, and the following elements carried by the stock, an actuator operable independently of the stock's shifting but in harmony with the upper needle, a reciprocable under needle actuated from said actuator, a looper adapted to coöperate with said under needle by a compound movement, a downwardly extending rigid looper-carrying lever, a universal pivot between the stock and lever located a substantial distance beneath said looper, a connection whereby the actuator bodily swings the lever to and fro about said universal pivot, and an adjustable follower mounted on said lever a substantial distance below said pivot, and a suitably-shaped cam fixed to said stock adapted to be engaged by the follower during the lever's to and fro movements. 45 50 55 60

In testimony whereof I affix my signature 65 in presence of two witnesses.

FRED A. READ.
